UNITED STATES PATENT OFFICE.

EDWARD PHREANER, OF PHILADELPHIA, PA., ASSIGNOR TO THE S. S.
WHITE DENTAL MANUFACTURING COMPANY, OF SAME PLACE.

MOTOR.

SPECIFICATION forming part of Letters Patent No. 249,984, dated November 22, 1881.

Application filed August 11, 1881. (No model.)

To all whom it may concern:

Be it known that I, EDWARD PHREANER, of the city and county of Philadelphia, in the State of Pennsylvania, have invented certain new and useful Improvements in Motors, of which the following is a specification.

My invention relates to certain improvements in water-motors for driving light machinery—such, for instance, as dental engines—10 which do not need much power, but necessarily require for their operating tools a very high rate of speed for boring, drilling, cutting, or working upon the tooth-substance.

The object of my invention is to provide a 15 superior and effective oscillating water-motor for light machinery, which may be connected to the ordinary service-pipes or hydrant-nozzle leading from a street-main and be operated by the force of the column of water passing 20 through such pipes or nozzle when a controlling cock or valve is opened for the flow of the current; and it consists in certain new constructions and combinations of parts or devices, which are recited at the close of this 25 specification.

In the accompanying drawings, Figure 1 is a vertical central section through the apparatus on the line 1 1 of Fig. 2, showing so much of the motor organized for driving a dental 30 engine as is necessary to an understanding of my improvements. Fig. 2 is a transverse section therethrough on the line 2 2 of Fig. 1. Fig. 3 is a view of the flat face of the oscillating cylinder of the motor, showing the horizontal or lateral ports or openings therein. Fig. 4 is a view of the plate, having recesses or 35 chambers and vertical wedge-shaped or tapering ports or openings, fitted to the flat face of said motor-cylinder and secured thereto so as 40 to oscillate therewith, as shown in Fig. 5; and Fig. 5 is a face view of the parts shown in Figs. 3 and 4 joined or secured together. Fig. 6 is a view of the stationary plate secured to the motor-casing and having vertical wedge-shaped 45 ports and recesses or chambers therein, to govern the admission of water to the motor-cylinder during its oscillation, and also provided with exhaust ports or openings; and Figs. 7 and 8 show different views of said stationary plate and oscillating parts of the motor fitted together for operation.

The motor-casing A is a closed metallic one, having a front plate, a, of glass, preferably, so as to permit of the ready inspection of the enclosed portions of the motor while at work. 55 The casing is mounted or secured upon any desirable or convenient support.

At or a little below the center of the casing, preferably, is hung the motor-cylinder B, so that it may oscillate upon trunnions or journals a' a' within the casing, as shown in Figs. 1 and 2. Said cylinder is preferably hung within its casing by two adjustable screw-journals or shafts projecting from the inner sides of the casing and having their inner ends cone-shaped or tapering to fit corresponding bearings or socket b b in the sides of the cylinder, whereby said cylinder may be accurately centered and any wear of the journals or bearings readily compensated for or taken up by adjustment. The cylinder B is preferably stopped at its lower end by a screw-plug, B', so that by removing said plug the interior of the cylinder may be readily reached for cleansing, fitting of the piston, or for other purposes. A piston, 65 C, is nicely fitted in said cylinder, so as to work up and down therein, the upper face or end of said piston receiving or being firmly connected to the lower end of the piston-rod C', which fits nicely in the box at the upper 70 end of said cylinder and passes therethrough, its upper end being connected to the crankpin d of a shaft, D, which is fitted to rotate in suitable bearings. Said shaft D in a dental engine carries a comparatively large driving 75 wheel or pulley, from which passes a belt connection or gearing to drive the operating tools through the medium of a light flexible driving-shaft, which permits the tools to be turned in various directions to do their work without interfering with their rapid rotary motion. 80

I have deemed it to be unnecessary to show the operative parts or upper works of a dental engine, as they constitute no part of my present invention. Nor is it necessary to show or 85 recite other light machines which may be driven by my improved motor.

The motor-cylinder B is oscillated upon its journals by the reciprocation of the piston C, which rotates the shaft D. The piston is reciprocated by the pressure of the water-column, which is admitted to the cylinder alter- 90 100

nately above and below said piston by the openings of the ports which control the entrance of the fluid.

Near the top and bottom of the cylinder, in its flat face, next the water supply or inlet pipe, are formed two horizontal transverse or lateral ports or openings, $b' b'$. A plate, E, is fitted water-tight to said flat face of the cylinder, and is secured thereto by screws, for instance, as shown in Fig. 5, so as to oscillate with the cylinder. In the face of said plate E, next to the flat face of the cylinder B, are formed enlarged recesses $e' e'$, one over each horizontal port b' of said cylinder, whereby chambers are formed to permit the spread of the water and its free distribution through the horizontal or transverse ports of the cylinder, to act forcibly upon the piston after the passage of the water through narrow vertical wedge-shaped or tapering ports $e' e'$ formed in said plate E. These wedge-shaped ports $e' e'$ have their widest ends at the upper and lower ends of the plate, or at the outer sweep of the cylinder when oscillated.

The front flat face of the plate E is fitted water-tight against the rear face of a plate, F, fastened in a permanent manner by screws, for example, to the side of the motor-casing A. The front face of said plate F, next to the side of the motor-casing, is provided with recesses or chambers $f' f'$, and these chambers communicate with inclined wedge-shaped ports or openings $f' f'$ in said plate, which correspond to the wedge-shaped ports $e' e'$ in the plate E of cylinder B. The said wedge-shaped ports $f' f'$ of the plate F are inclined, it will be seen, instead of being exactly vertical, so that whenever one of the vertical ports of the plate E is open or in line with one of the ports in the plate F during the oscillation of the cylinder the other vertical port of said plate E will be cut off from the water-supply by being carried away from the opposite port of the plate F. (See Fig. 7.) In being shut off from the fluid supply, however, the port in the plate E is carried opposite the exhaust opening or recess f^2 in the back of the plate F, and consequently the exhaust of the spent fluid is permitted from the end of the cylinder opposite to that receiving the impact of the fluid-column to move the piston.

The recesses or chambers $f' f'$ of the plate F are directly opposite two feed-openings, $a^2 a^2$, in the side of the casing A, leading from the inlet or supply pipe G, and the water enters said chambers to pass alternately through the upper and lower wedge-shaped ports of the motor to the cylinder as said ports are alternately opened, in order to reciprocate the piston, rotate the shaft D, oscillate the motor-cylinder, and drive the machine to be operated from said shaft. Said inlet or supply pipe G is connected with the ordinary service-pipes or with a hydrant-nozzle of the usual street-main, the pressure of water from such a main being sufficient to oscillate the motor and drive the machine.

A suitable stop-cock or controlling-valve is applied to the inlet-pipe to turn on or shut off the flow of water, as desired.

The operation of the machine is as follows: Suppose the piston in the cylinder to stand in the position shown in Fig. 1, which is the extreme limit of its upward movement. The upper wedge-shaped port of the plate E has been closed against the fluid-supply, and the exhaust has taken place through said port and the exhaust-recess f^2 in the back of the plate F. As soon as the piston has reached the upper limit of its movement the rotation of the shaft D and of its crank-pin d has so far progressed as to have turned the cylinder on its journals, so as to open the upper port of the plate E to the fluid-supply, while closing the lower port of said plate to said supply, and the exhaust now takes place through said lower port and the exhaust-recess f^2 , opposite which recess the lower port of the plate E has been brought by the oscillation of the cylinder. The piston is now forced down by the water to its lowest position in the cylinder, completing the rotation of the shaft, and this reciprocation of the piston is continued as long as the water is supplied to the motor in order to drive the machine.

It will be seen from the organization of my improved motor that the vertical wedge-shaped ports open very quickly, with but little oscillation of the cylinder, and as large as the horizontal or transverse ports of the cylinder, whereby I get the full force of the fluid-column in the shape of quick blows upon the piston. The exhaust takes place at the opposite end of the cylinder from that at which the water enters to move the piston without affording such resistance as to detract from the effectiveness of the motor. The exhausted or spent fluid escapes first into the casing, and from thence it passes away into the drain or sewer through the comparatively large escape or waste pipe H leading from an opening in the bottom of the casing.

The escape-pipe H affords an excellent means of mounting the motor. Said pipe may be inserted, for instance, in a hollow upright standard, so that the motor may have the capacity of turning upon said standard.

I claim as my invention—

1. The combination, substantially as herein-before set forth, of the casing, the oscillating cylinder provided with the horizontal or transverse ports or openings, the piston, the inlet or supply pipe, and the vertical ports between said inlet or supply pipe and said cylinder.

2. The combination, substantially as herein-before set forth, of the casing, the oscillating cylinder having the horizontal ports therein, the piston, the shaft with which said piston is connected, the supply-pipe, the recessed plates between said supply-pipe and cylinder having wedge-shaped or tapering ports therein, and the escape-pipe for the spent or exhausted fluid.

3. The combination, substantially as herein-

before set forth, of the oscillating cylinder having the horizontal or transverse ports therein, and the plate fastened to said cylinder so as to oscillate with it, having recesses communicating with said horizontal ports of the cylinder, and vertical ports communicating with said recesses.

In testimony whereof I have hereunto subscribed my name this 3d day of August, A D. 1881.

EDW. PHREANER.
